UNITED STATES PATENT OFFICE.

CHARLES G. BAUER, OF BROOKLYN, NEW YORK.

ELECTRICAL HORN.

1,232,185.

Specification of Letters Patent.

Patented July 3, 1917.

Application filed August 1, 1916. Serial No. 112,582.

To all whom it may concern:

Be it known that I, CHARLES G. BAUER, a citizen of the United States, residing at Brooklyn, in the county of Kings and State 5 of New York, have invented new and useful Improvements in Electrical Horns, of which the following is a specification.

This invention relates to improvements in electrical horns and has particular application to a horn of the diaphragm type.

In carrying out the present invention, it is my purpose to improve and simplify the general construction of electrically operated horns and to provide a horn which will be found especially useful on motor vehicles and for warning signals.

It is also my purpose to provide a horn of the class described which will embody comparatively few parts and these so arranged and correlated as to reduce the possibility of derangement to a minimum.

With the above and other objects in view, the invention consists in the construction, combination and arrangement of parts hereinafter set forth in and falling within the scope of the claims.

In the accompanying drawing:

Figure 1 is a vertical sectional view through a horn constructed in accordance 30 with the present invention.

Fig. 2 is a rear elevation of the same, the casing being removed.

Fig. 3 is a sectional view through the horn taken at right angles to Fig. 1.

Referring now to the drawing in detail, 35 1 designates a cup-shaped casing having the side wall at the open end thereof formed with an outturned flange 2 and integral with the outer edge of the flange 2 is a circular flange 3. Arranged across the open end of the casing 1 is a disk 4 having the outer edge portion seated against the flange 2 and the central portion formed with an opening 5, while arranged upon the outer edge portion 40 of the disk 4 at the outer side thereof and confined within the flange 3 is a washer 6 and resting upon the washer 6 is the outer edge portion of a circular diaphragm 7. 8 designates a circular disk having the outer 45 edge portion offset inwardly and bearing upon the corresponding portion of the diaphragm 7 and passed through the outer portions of the disk 8, the diaphragm, the washer, the disk 4 and the flange 2 are securing screws or bolts 9. The disk 8 is formed centrally with a relatively large

opening 10 and secured within this opening and projecting outwardly from this disk is an amplifying horn 11, while secured to the inner face of the disk 4 is a magnetic 60 coil 12 wrapped about an annulus 13 forming the core of the magnet and having the inner wall thereof V-shaped in cross section. Secured to the inner side of the diaphragm 7 at the center thereof is an armature 14 65 shaped after the fashion of a frustum of a cone to conform to the shape of the adjacent portion of the pole of the magnet. Fastened to the inner side of the disk 4 beyond the magnet is a substantially U-shaped 70 bracket 15 and secured to the central member of the bracket 15 and projecting over the magnet is a spring arm 16. Fastened to one side of the spring arm 16 is a disk 17 formed with a frusto-conical armature 75 18 disposed within the influence of the pole 13, while fastened to the other side of the spring arm 16 is a disk-like plate 19 formed with a rearwardly extending pin 20. 21, 21 80 designate bracket arms secured to the disk 4 at diametrically opposite sides of the magnet coil 12 and fastened to one of these bracket arms is one end of a spring contact arm 22 having the other end overlapping the other bracket arm 21 and adapted 85 to engage a contact 23 carried by such other arm. The spring arm 22 normally tends to disengage the contact 23, and the fixed end of the arm is connected to one terminal of the magnet coil 12, while the remaining 90 terminal of such magnet coil and the contact 23 are adapted to be connected to the respective terminals of an electric circuit including a suitable source of energy and a switch. As long as the magnet 12 is de- 95 energized, the spring arm 16 under the weight of the disks 17 and 19 swings away from the magnet and the pin 20 engages the contact arm 22 to hold the latter in engagement with the contact 23. When the switch 100 is closed, current flows through the magnet coil, the contact arm 22 and the contact 23, thereby energizing the coil and upon the energization of the coil, the armatures 14 and 18 are drawn toward the respective sides 105 of the core and engage each other with the effect to vibrate the diaphragm 7 so that sound waves may be transmitted through the horn 11. As long as the magnet 12 is energized, the contact arm 22 is relieved of 110 the influence of the pin 20 and disengages the contact 23, thereby deenergizing the

magnet so that the armatures may be restored to normal position and this alternate energizing and deenergizing of the magnet continues as long as the switch in the circuit is closed, thereby vibrating the diaphragm 7 rapidly to sound the horn.

While I have herein shown and described the preferred form of my invention by way of illustration, I wish it to be understood that I do not limit or confine myself to the precise details of construction herein described and delineated, as modification and variation may be made within the scope of the claims and without departing from the spirit of the invention.

I claim:

1. A horn of the class described comprising a casing having an open end, a disk secured to the open end of said casing and formed centrally with an opening, a diaphragm having the peripheral edge thereof secured to the outer surface of said disk and spaced apart therefrom, a magnetic coil secured to the inner side of said disk concentrically of the opening therein and having an annular core V-shaped in cross section, a frusto-conical shaped armature secured to said diaphragm at the center thereof and disposed within the influence of one side of said pole, a make and break device connected in circuit with the magnet, a frusto-conical armature connected to said device and disposed within the influence of the other side of the pole of said magnet whereby the circuit of the magnet may be alternately opened and closed automatically and the diaphragm vibrated rapidly.

2. A horn of the class described comprising a casing having an open end, a disk secured to the open end of said casing and formed centrally with an opening, a diaphragm having the peripheral edge thereof secured to the outer surface of said disk and

spaced apart therefrom, a magnetic coil secured to the inner side of said disk concentrically of the opening therein and having an annular core V-shaped in cross section, a frusto-conical shaped armature secured to said diaphragm at the center thereof and disposed within the influence of one side of 45 said pole, a make and break device connected in circuit with the magnet, a frusto-conical armature connected to said device and disposed within the influence of the other side 50 of the pole of said magnet whereby the circuit of the magnet may be alternately opened and closed automatically and the diaphragm 55 vibrated rapidly, a disk secured to the outer side of said diaphragm at the periphery thereof and spaced apart therefrom and formed centrally with a relatively large opening, and a horn secured in the last-named opening.

3. A horn of the class described comprising a casing having an open end, a disk secured to the open end of the said casing and formed centrally with an opening, a diaphragm having the peripheral edge thereof secured to the outer surface of said disk and spaced apart therefrom, a magnetic coil secured to the inner side of the said disk concentrically of the opening therein and having an annular core, an armature secured to said diaphragm at the center thereof and disposed within the influence of one side of 65 said core, a make and break device connected in circuit with said magnet, and an armature connected with said device and disposed within the influence of the other side of said core of the magnet, whereby the circuit of 70 the magnet may be alternately opened and closed automatically and the diaphragm vibrated rapidly.

In testimony whereof I affix my signature.

CHARLES G. BAUER.
